T. GLOVER,
CONSTRUCTION OF COIN CARRIERS FOR COIN FREED MECHANISM.
APPLICATION FILED OCT. 24, 1919.
1,367,370. Patented Feb. 1, 1921.

UNITED STATES PATENT OFFICE.

THOMAS GLOVER, OF EDMONTON, LONDON, ENGLAND.

CONSTRUCTION OF COIN-CARRIERS FOR COIN-FREED MECHANISM.

1,367,370.

Specification of Letters Patent.

Patented Feb. 1, 1921.

Application filed October 24, 1919. Serial No. 332,971.

To all whom it may concern:

Be it known that I, THOMAS GLOVER, a subject of the King of Great Britain, residing at Edmonton, London, England, have 5 invented certain new and useful Improvements in the Construction of Coin-Carriers for Coin-Freed Mechanism, of which the following is a specification.

This invention relates to that class of coin 10 carrier for coin freed mechanism constructed from two slotted cups arranged with the open ends next to each other one being fixed to the shaft carrying the operating handle and the other loosely arranged 15 on the shaft and connected with the operating mechanism, the shaft being cranked or cut away within the cups to permit the coin to rest within the cups, preferably with one portion of the edge exposed.

20 Now the object of this invention is to construct such cups in such a way that they may be operated by either a penny or a halfpenny, or by two different sized coins, say one shilling and a sixpence, the mechanism 25 being operated only according to the value of the coin.

My invention will be clearly understood from the following description aided by the annexed drawings in which—

30 Figure 1 is a perspective elevation of the two cups and shaft, the cups being detached.

Fig. 2 is a plan view of the cups and shaft in assembled relation, and showing in broken lines the handle and one form of 35 gear and also the relative positions of the two coins.

For the purpose of this invention I construct the cups A, B of two different diameters and in the larger A, I cut two coin 40 slots C, D at an angle of 90° to each other while in the smaller cup B, I cut four coin slots E, each at an angle of 90° to the next succeeding slot. In the larger cup A I bend in the outer corner F of a wall of one slot 45 to approximately the outer diameter of the smaller cup B, or I may provide a pin or other device at the corner.

In the ordinary construction of devices of 50 this character the cups A, B are operated one half a revolution for each coin inserted,

but in the construction according to my invention for say the penny the cups A, B are revolved a one half revolution while for the halfpenny the larger cup A is revolved a one half revolution and the smaller cup 55 B is only revolved a one quarter revolution, so that the mechanism for a halfpenny is only moved half the amount of the movement for the penny.

On dropping in the penny after the two 60 cups A, B have been properly positioned to receive the coin, when the handle G is turned the coin is gripped between the walls of the slots C, E in the two cups A, B and all are turned a half revolution. The 65 movement is then stopped as usual and the coin discharged. The cup B has a plurality of notches H in its periphery adjacent to the slots E in which a spring pawl H' engages when the cup is in position to discharge the 70 coin. The handle shaft I and the larger cup A are now turned in the opposite direction in order that the slots C and E in the two cups A, B may coincide to receive a fresh coin, and the action will be the same 75 if a penny is dropped in, but if a halfpenny, which is smaller in diameter than the external diameter of the cup A is dropped in it finds a position fully within the larger cup A, and this being free from action on 80 the halfpenny at that position, will, on being revolved, travel around a quarter revolution without acting on the coin and then the bent corner F will engage the halfpenny which will be gripped by the two cups A, B 85 and the two cups will revolve another quarter of the revolution before the coin is discharged so that the larger cup will revolve its full distance while the smaller cup will only be revolved a quarter of a revolution and the mechanism only moved accordingly.

What I do claim as my invention, and desire to secure by Letters Patent, is:—

Coin carriers for coin freed mechanism 95 comprising two cups of different diameters, an operating shaft carried by the larger cup, the other cup surrounding the shaft and connected with the coin feed mechanism, the cup of larger diameter having two 100

slots arranged at an angle of ninety degrees to one another and having the corner of the wall of one slot bent toward the axis of the cup to coincide with the periphery of the smaller cup, the smaller cup having four slots each at an angle of ninety degrees to the next succeeding slot.

In testimony whereof I have hereunto set my hand in presence of two subscribing witnesses.

THOMAS GLOVER.
